UNITED STATES PATENT OFFICE.

FREDERICK C. HAYES, OF BATTLE CREEK, MICHIGAN.

CIGAR BANDING OR LABELING MACHINE.

969,057.

Specification of Letters Patent. Patented Aug. 30, 1910.

Application filed June 21, 1909. Serial No. 503,502.

To all whom it may concern:

Be it known that I, FREDERICK C. HAYES, a citizen of the United States residing at the city of Battle Creek, county of Calhoun, 5 State of Michigan, have invented certain new and useful Improvements in Cigar Banding or Labeling Machines, of which the following is a specification.

This invention relates to improvements in 10 cigar labeling or banding machines.

The main objects of this invention are: First, to provide an improved cigar labeling machine by which the cigars may be rapidly and effectively banded without danger of 15 injury thereto. Second, to provide an improved cigar labeling machine which is easy and simple to operate. Third, to provide an improved cigar labeling machine which is entirely automatic in its operation, except 20 the feeding of the cigars to the machine,— that is, the labels are fed and applied to the cigars automatically. Fourth, to provide in a cigar labeling machine, an improved means for applying the labels or bands. Fifth, to 25 provide in a cigar labeling machine, an improved moistening mechanism for the labels. Sixth, to provide an improved cigar labeling machine which is very compact in structure. Seventh, to provide an improved cigar labeling 30 machine which is not likely to be disarranged, and one in which the label feeding mechanism is not likely to become clogged.

Further objects, and objects relating to structural details will definitely appear from 35 the detailed description to follow.

I accomplish the objects of my invention by the devices and means described in the following specification.

The structure described constitutes one effective embodiment of my invention. Other 40 embodiments would be readily devised by those skilled in the art.

The invention is clearly defined and 45 pointed out in the claims.

A structure constituting an effective and 50 preferred embodiment of the features of my invention is clearly illustrated in the accompanying drawing, forming a part of this specification, in which:

Figure 1 is a side elevation of a structure 55 embodying the features of my invention, the table or support being omitted, the actuating connecting rod or pitman being broken away and the delivery chute being shown

in vertical section. Fig. 2 is a plan view of 55 the structure appearing in Fig. 1. Fig. 3 is a vertical section taken on a line corresponding to line 3—3 of Fig. 2. Fig. 4 is an enlarged detail vertical section taken on a line corresponding to line 4—4 of Fig. 2, 60 showing details of the operating or driving mechanism, the parts being shown in their actuated position by dotted lines. Fig. 5 is a detail elevation of certain of the parts shown in Fig. 4. Fig. 6 is an enlarged 65 detail vertical section taken on a line corresponding to line 6—6 of Fig. 2, showing further details of the driving mechanism or connections. Fig. 7 is an enlarged detail 70 of one of the apron driving rollers taken on a line corresponding to line 7—7 of Fig. 6, the roller being shown in full lines. Fig. 8 is an enlarged detail vertical section through the label hopper and feeding mechanism, parts being shown in full lines. Fig. 75 9 is an enlarged detail side elevation of the label feeding foot, showing the means for elevating it on its return movement, the movements of the parts being indicated by dotted lines. Fig. 10 is a detail vertical section 80 through the label feeding mechanism, taken on a line corresponding to line 10—10 of Fig. 8. Fig. 11 is an enlarged detail horizontal section taken on a line corresponding to line 11—11 of Fig. 1, showing the details of the label feeding mechanism. Fig. 12 is an enlarged detail horizontal section 85 corresponding to that of Fig. 11, the parts being illustrated in another position. Fig. 13 is a detail vertical section taken on a line 90 corresponding to line 13—13 of Fig. 1. Fig. 14 is an enlarged horizontal section taken on a line corresponding to line 14—14 of Fig. 3, showing details of the label hopper. Fig. 15 is a detail of the band applying 95 mechanism, one of the cigar holders being shown closed upon a cigar and one being shown open. Fig. 16 is an enlarged detail vertical section of the trip for the cigar holders, taken on a line corresponding to line 16—16— of Fig. 2. Fig. 17 is an enlarged detail perspective of one of the equalizing rollers for the cigar supporting bands. Fig. 18 is a detail section taken on a line corresponding to line 18—18 of Fig. 17. Fig. 19 is a detail of the tension device 100 for supporting the hopper bottom. Fig. 20 is a detail vertical section taken on a line

corresponding to the line 20 of Fig. 1, showing details of the label feed table. Fig. 21 is an enlarged detail side elevation of the trip means for the clutch 118, the arm being shown in dotted lines in the position it occupies at the time of the release of the trip member. Fig. 22 is a plan view of the trip member 123. Fig. 23 is a detail side elevation showing the label moistening device in its actuated position.

In the drawings, similar reference characters refer to similar parts throughout the several views, and the sectional views are taken looking in the direction of the little arrows at the ends of the section lines.

Referring to the drawing, the frame 1, on which the parts are mounted, is preferably mounted on a table or support so that the operator can operate the machine when seated in front of the table or support. I will first describe the means for applying the bands or labels to the cigars, and then the means for feeding the labels. In Fig. 3, which is a vertical, transverse section through the machine, the relation of the parts clearly appears.

The band-applying mechanism, as illustrated, consists of a driving shaft 2 on which is mounted the supporting spiders or heads 3, the heads being fixed to the shaft. Upon each of these spiders or heads are a series of radially-projecting arms 4 and 5, arranged in pairs, the arms 4 being rigid and the arms 5 being pivoted at 6 to swing toward and from the arms 4. The corresponding arms 4 of each head 3 are connected by cross pieces 7, while the corresponding arms 5 are connected by cross pieces 8, so that the spiders or heads 3 and their arms 40 and cross bars 7 form a rigid reel-like structure on which the arms 5 are pivotally mounted, as stated.

A series of belts or aprons 9 is provided for supporting and applying the labels to the cigars, the cigars as 10 being indicated in position in the apparatus in Fig. 3, the cigars being indicated in conventional form. These belts or aprons 9 are carried by the driving rollers 11, and the carrying rollers 12, the carrying rollers 12 being mounted at the outer ends of the arms 4 and 5, while the driving rollers 11 are arranged in suitable bearings on the heads 3 illustrated in detail in Fig. 7, which will be described later. These carrying and driving rollers are arranged, when the arms 5 are in their extended position, in a triangular relation, as clearly appears in the drawing to provide a horizontal portion for the apron upon which the cigars may be placed. The shafts 13 of the driving rollers 11 are provided with pinions 14, each of which is arranged to mesh with the gear 15,— see Fig 6.

I preferably arrange adjacent to each

driving roller a friction idler 16—see Fig. 65 3,—these idlers being arranged to hold the carrying belts 9 against the driving rollers, so that they are more positively driven. One of each pair of supporting rollers may be driven from the driving roller or by a 70 driving belt 16', if desired. Each belt is also preferably provided with a pair of tension or compensating idlers 17 arranged to engage the belt from opposite sides. These tension idlers are carried by the pivoted 75 yokes 18, which are mounted on the cross pieces 19, carried by the arms 4. The yokes 18 are provided with transversely-arranged bearing portions 20, which are engaged by the pivot bearings 21 carried by the arms 80 22 on the cross piece 19. This support for the idler rolls 17 allows them to adjust themselves to maintain a proper tension on the belt to accommodate the same to cigars of different shapes or sizes,—that is, the 85 proper driving and supporting tension is maintained on the belt which is preferably formed of rubber, or suitable elastic material. The details of these tension or compensating rollers are illustrated in Figs. 17, 90 and 18.

The apron driving rollers 11 are preferably supported by pivot bearings 23 which are made adjustable to permit the ready insertion or removal of the rollers and their accurate adjustment. The bearing pivots at the righthand side of the structure illustrated are carried by a supporting ring 24 provided therefor, the ring being carried by arms 25, projecting from the righthand head 3. The object of this is to bring the pinions 14 on the shafts 13 of the driving rollers concentric to the driving gear 15. The details of these parts are illustrated in Fig. 2.

The gear 15 is driven through the ratchet 26 and the pawl lever 27, the lever being provided with a dog or pawl 28 to engage the ratchet wheel. The ratchet wheel is mounted on the hub 29 of the gear 15, which is revolubly mounted on the shaft 2. The pawl lever 27 is connected by a connecting rod 30 to suitable treadle, or other actuating means, not here illustrated, the apparatus being designed, where manually operated, to be operated through a treadle or other foot power mechanism. This lever 27 is also adapted to advance the label applying mechanism with a step-by-step movement, the label applying mechanism being advanced on the up stroke of the lever and the gear 15 being driven on its down stroke. To accomplish this, the lever is provided with a pawl 31 pivoted on the lever at 32, and adapted to engage the internal ratchet wheel 33, which is provided with teeth corresponding to the number of aprons on the label applying mechanism and secured upon the

shaft so as to bring these several aprons into proper position to receive the labels. The wheel 33 also serves as a locking wheel, it being provided with a flange-like rim having holes 34 therein arranged to correspond with the arrangement of the teeth, the holes being adapted to receive the locking dog 35. This dog 35 is provided with a stem 36 arranged through a double armed bracket 37 on the frame, a coiled spring 38 being provided for holding the dog yieldingly downward. This dog is arranged to be disengaged by the pawl 31, the pawl first disengaging the dog and then turning the wheel 33 and through it actuating the label applying mechanism. The pawl 31 is held in engagement with the teeth of the wheel 33 by means of the spring 39. Details of these parts are illustrated in Figs. 4 and 5. By this connection, through the operation of the lever 27, the label applying mechanism is advanced with a step-by-step movement and actuated to apply the labels. When it is desired to release the label applying mechanism so that it may be freely turned to any position, the locking dog 35 is held out of its engaging position by means of the cam lever 49, which is pivoted on the upper end of the stem 36, so that the stem may be raised and held out of engaging position thereby.

In operating the device, the cigars are laid by the operator upon the uppermost apron, over which a label projects, as is indicated by dotted lines in Fig. 3, the pivoted arms 5 are swung by the operator toward their coacting arms, so that the cigar is clamped by the apron, as is indicated in Fig. 3. This can be quickly and easily done, and the remaining operations in applying the bands are entirely automatic,—that is, as the cigars are carried forward to the place of discharge, they are rotated by the aprons to properly wrap the labels thereon, and the labels are retained on the cigars as they are carried forward, so that a sufficient amount of time elapses to permit the setting of the adhesive.

When the arms 5 are swung rearwardly to clamp the cigars in the aprons, they are retained in their clamping position by means of the latches 40, which are pivoted at 41 on the fixed arms and provided with notches 42 to engage the pins 43 on the swinging arms,—see details in Fig. 15. Springs 44 are provided for holding these arms in engagement. These springs also return the swinging arms to their open or outer position, one end of the spring being secured to the inner ends 45 of the swinging arms, beyond their pivots.

At the desired point, the cigars are ejected by tripping the latches 40, a trip 46 being arranged to be successively engaged by

the projecting pins or trips 47 on the latches, 65 see Figs. 2, 15 and 16. A suitable chute, as 48, is arranged to receive the cigars as they are ejected from their carriers.

Having thus described in detail the label applying portion of my improvements, I will now describe the label feeding and moistening device. The labels, as 50, are placed in a suitable hopper 51 at the rear of the mechanism described and below the feeding mechanism proper. The hopper 51 is adapted to be slipped into a suitable frame 52 provided therefor. The hopper 51 is preferably made up of a pair of side walls 53 and an end wall 54, which serves to connect the side walls.

To adapt the hopper for labels of different widths, I preferably provide the same with adjustable vertically-arranged side members 55, which are supported in the guides 56 on the side walls by means of the screws 57, so that the hopper can be adjusted to the labels to prevent their becoming displaced laterally therein. The details of this adjustable feature are illustrated in Fig. 14.

The hopper is provided with a false bottom 58 on which the labels rest, the bottom being provided with cross pieces 59, one of which is adapted to engage the rests 60 at the forward end of the hopper, and the other to rest on the pivot rods 127. The false bottom 58 is carried by the bottom 62, which is mounted on the upper end of the vertically adjustable bottom supports 63. These supports are arranged through suitable guide bearings 64 to be vertically adjusted and thus feed the labels upward in the hopper. These supports are held yieldingly upward by means of the drum 65 and spring 66, wound thereon, the shaft 67 of the drum being connected through the cord 68 to the cross piece 69 at the lower ends of the supports. This cross piece is pivoted at 70 to one of the supports, and has a slip connection by means of the slot 71 and the pin 72, with the other support, so that a tilting 110 of the bottom is permitted, the bottom being pivoted on one support at 73, the other support being provided with a supporting roller 74, on which the bearing block 75 of the bottom rests. This permits the adjustment of the bottom to any variation in thickness of the labels, as, when the adhesive is applied to the labels before they are placed in the hopper, the end having the adhesive thereon will be thicker than that of the other end, and this connection permits of a complete adjustment and prevents binding of the parts.

The drum 65 is provided with a suitable pawl and ratchet wheel 76 and 77, respectively, to permit the winding of the spring. The details of this drum and the bottom supports are illustrated in Figs. 3, 8, and 19.

The labels are advanced one by one to the label applying mechanism, and to properly time this label feeding carriage 78 it is operatively connected to the label applying mechanism. The connections preferably 5 consist of the lever 79 which is pivoted on the frame 1 at 80. The lever 79 is connected by the link 81 to the arm 83 on the actuating lever 27 and by the link 82 to the arm 83 on the carriage. The lever 79 is 10 provided with arms 84 to which the links 81 and 82 are respectively connected.

A feed table 85 is provided for the labels, the table extending from the hopper to the label applying mechanism. This table is 15 preferably adjustably supported by means of the screw 86, which is arranged through the hopper frame to engage a yoke-like arm 87 on the downwardly-projecting portion 88 of the way, which downwardly-projecting portion forms the front of the hopper proper.

By connecting the carriage as described, the feeding of the labels is properly timed 20 to the movements of the wrapping or band applying mechanism. On the under side of the carriage is a label engaging foot 89 which engages the labels and feeds them forwardly on the table 85, as the carriage is advanced. This table is preferably 25 provided with a longitudinal groove 85', see Fig. 20, to afford the foot a more secure grip upon the label. The foot is also preferably provided with a rubber facing 90 to make its hold upon the labels more secure. 30 The foot 89 is carried by an arm 91, which is pivoted at 92 on the hanger 93. The foot 35 93 is preferably adjustably mounted on the arm 91, which has a slot 116 for the securing screws 117. The hanger 93 is slotted at 40 its lower end to receive the arm 91, the inner end 94 of the slot 95 serving as a stop to limit the downward drop of the foot.

The hanger 93 is preferably pivoted at 45 96 and provided with an arm 97, which projects forwardly over the arm 91. On this arm 97 is a spring 98, which engages the arm 91 holding it yieldingly downwardly and in engagement with the stop 94. The foot is 50 adjusted to limit its downward movement by adjusting the hanger and this is preferably accomplished through the carriage to engage the arm 97. A pin 100, arranged 55 transversely through the screw, prevents its longitudinal movement.

The carriage is arranged to reciprocate in ways 101. In operation, the foot 89, engaging the rear end of the label, carries its rear 60 end forward, while its forward end is still engaged by the retaining clamps 102, causing the label to bend or loop upwardly at its center, as is shown in Fig. 8. When the forward end of the label is released, it moves 65 onto the ways or table 85 and is carried for-

wardly until it is projected over one of the belts or wrapping aprons 9 in position to receive a cigar. As the foot 89 reaches the end of its forward movement, the label is grasped or clamped by the clamps 103, 70 which are arranged in pairs to swing inwardly and downwardly upon the delivery table.

The return ways 104 are provided for the foot 89, and these are preferably mounted 75 upon or formed integrally with the clamps 103, the forward ends of the ways being inclined downwardly to engage the transversely-arranged pin 105 on the foot to elevate the foot on the rearward movement of 80 the carriage. This rearward movement of the carriage actuates the moistening device, which preferably consists of a receptacle 106, which is mounted on the rear end of the conduit 107, the conduit being pivoted 85 at 108 on the upwardly-projecting arm 109 of the frame.

On the forward end of the conduit 107 is a brush or applicator 110 which is brought into contact with the gummed portion of 90 the label which has been advanced to the band applying mechanism on the return stroke of the feed carriage. A valve 111, shown only in conventional form, is provided for regulating the feed of the moistening device. The moistening device is actuated by an upwardly-projecting arm 112 on the carriage, which arm is provided with a laterally-projecting pin 113 arranged to engage the cam like member 114 coacting on 95 the rear end of the conduit 107. This rocks the conduit and brings the applicator 110 into contact with the label. The actuating member 114 is provided with a spring portion 115 at its forward end to permit the 100 trip pin on the arm 112 to move forwardly without actuating the applicator.

As the label engaging foot moves the rear 105 end of the top label forward, as illustrated in Fig. 8, the rear ends of the remaining 110 labels are engaged by the clamp 118, which is pivoted at 119 at the rear end of the hopper frame. This clamp is held yieldingly in its engaging position by means of the coiled spring 120 on the pivot 119, one end 115 of the spring being secured to the brackets 121 on the frame by which the clamp is carried, and the other to the clamp.

On the rear end of the clamp is an upwardly-projecting arm 122, which is, on the 120 rearward movement of the carriage, engaged by the releasing or tripping cam 123 on the carriage. This cam is preferably a spring secured to the block 124 at its center, so that the engaging pin 125 on the arm 122 125 passes over the trip on the forward movement of the carriage, permitting the clamp to remain in its engaging position.

Within the hopper I provide side clamps 130 adapted to engage the edges of the upper

labels. These clamps 126 are arranged in pairs and are mounted on the pivot rods 127 at the lower portion of the hopper, so that the clamps project upwardly at the sides of 5 the labels. These clamps are held yieldingly in their engaging position by means of the coiled springs 128, which are arranged within the hopper so that they engage the cross pieces 129, by which the 10 clamps 126 are connected, the other ends of the springs engaging the walls of the hopper,—see Fig. 13. These clamps 126 are actuated by the levers 130, which are arranged one on each side of the hopper. 15 These levers are mounted on the pivot rods 131 and are connected to actuate the clamps 126 through the screws 132, which are adjustably arranged in the levers to engage the cross pieces, connecting the clamping arms 20 through holes 133 in the hopper frame 52.

The levers are actuated by springs 134, one end of which is arranged to engage the pin 135 on the levers and the other engaging the sides of the hopper frame. See Figs. 25 1 and 13.

The levers 130 are provided with upwardly-projecting pin-like engaging members 136, which are engaged by a pair of guide ways 137 on the under side of the carriage. These ways are provided with cam portions 138 at their forward ends, which permit the arms or levers 130 to swing outwardly and actuate the clamps 126 during the passage of the engaging foot over the 30 labels, thus supporting the labels so that the top label slips freely across the same, preventing the sagging or forming of pockets in the labels as the engaging foot is removing the upper one.

40 At the rear ends of the cams 138 are springs 139 which prevent the passing of the engaging members 137 into the cams on the rearward movement of the carriage and at its forward end are guide springs 140, 45 which cause the engaging members to drop into the cams.—See Fig. 11.

Thus the parts are actuated, and their actuation properly timed relative to the movement of the label engaging foot 89.

50 To cause the labels to take the position shown in Fig. 8, when the rear end is engaged by the shoe 89, I clamp their front ends during a short period of the carriage movement, the clamps 102 being arranged 55 to swing down upon the labels, the clamps being arranged in opposed pairs. These clamps are pivoted at 141 and are connected by the links 142 to the arms 143, which are, in turn, mounted on the pivot rods 131, the 60 arms being fixed to the pivot rods by means of the set screws 144. See Fig. 13. To actuate the arms 143, the pivot rods 131 are provided with arms 145, having engaging members 146 at their upper ends, which are 65 adapted to engage the guide ways 137 so

that these clamps are also controlled by the movement of the carriage, and the movement thereby properly timed relative to the other parts. By this means, the labels are effectively supported so that a single label 70 is fed at each stroke of the carriage and without liability of the apparatus being clogged or the labels being torn or distorted thereby. The clamps 103 are mounted on pivots 147 carried by the supports 148 and 75 149, respectively. A spring 150 is provided for each clamp, the spring being secured to the clamps 103 at one end and to the arms of the clamps 102, the spring preferably forming a pivot 141 for connecting the links 80 142 to such clamps, so that, as these clamps 102 are released, the clamps 103 are also released and permitted to swing up to permit the feeding of the next label. As previously stated, the return ways 104, for the label 85 engaging foot, are carried by these clamps, thus securing a proper timing and actuation of the feeding mechanism and clamps.

My improved label feeding mechanism is very accurate,—that is, it effectively feeds 90 a label at each stroke or movement thereof, and does this without injury to the labels. The apparatus illustrated is adapted for the feeding of the gummed labels,—that is, the applicator illustrated is designed for the 95 application of moisture to the gummed portion of the label. The apparatus could, however, be readily adapted to the feeding of adhesive material, so that ungummed labels could readily be used.

100 While the feeding mechanism is particularly adapted and designed by me for use in connection with my improved band applying mechanism, it is obvious that it could be used with various forms of band applying mechanism.

I have illustrated and described my improved labeling machine substantially in the form in which I have embodied the same in practice. I am, however, aware that it is 110 capable of being very greatly varied in structural details without departing from my invention. These variations are, however, so numerous that I do not attempt to illustrate or describe them in detail therein, 115 but I wish to be understood as claiming my invention in detail in the form illustrated, but also broadly.

Having thus described my invention, what I claim as new and desire to secure by Letters Patent is:

1. The combination with a shaft having spiders or heads thereon provided with radially-projecting arms arranged in coacting pairs, one arm of each pair being pivoted to swing toward the other; a plurality of aprons or belts; driving and supporting rollers therefor arranged on said heads; latches for retaining said pivoted arms in their closed positions; springs for returning 125 130

1. said pivoted arms to their open positions when the said latches are disengaged; a trip adapted to successively disengage said latches; pinions for the driving rollers; a driving gear therefor revolubly mounted on said shaft; a ratchet wheel connected to said driving gear; an actuating lever; a pawl thereon arranged to engage said driving gear ratchet; an internally-toothed ratchet driving wheel for said shaft having a flange-like periphery with holes therein spaced to correspond to its teeth; a locking dog arranged to engage said openings in the periphery of said shaft driving wheel; and a pawl on said actuating lever arranged to engage said shaft driving ratchet, said pawl being adapted to first disengage said locking dog and afterward advance said wheel.
2. The combination with a shaft having spiders or heads thereon provided with radially-projecting arms arranged in coacting pairs, one arm of each pair being pivoted to swing toward the other; a plurality of aprons or belts; driving and supporting rollers therefor arranged on said heads; latches for retaining said pivoted arms in their closed positions; springs for returning said pivoted arms to their open positions when the said latches are disengaged; a trip adapted to successively disengage said latches; pinions for the driving rollers; a driving gear therefor revolubly mounted on said shaft; a ratchet wheel connected to said driving gear; an actuating lever; a pawl thereon arranged to engage said driving gear ratchet; a ratchet driving wheel for said shaft; a locking dog for said shaft driving wheel; and a pawl on said actuating lever arranged to engage said shaft driving ratchet, said pawl being adapted to first disengage said locking dog and afterward advance said wheel.
3. The combination with a shaft having spiders or heads thereon provided with radially-projecting arms arranged in coacting pairs, one arm of each pair being pivoted to swing toward the other; a plurality of aprons or belts; driving and supporting rollers therefor arranged on said heads; latches for retaining said pivoted arms in their closed positions; springs for returning said pivoted arms to their open positions when the said latches are disengaged; a trip adapted to successively disengage said latches; pinions for the driving rollers; a driving gear therefor revolubly mounted on said shaft; a ratchet wheel connected to said driving gear; an actuating lever; a pawl thereon arranged to engage said driving gear ratchet; a ratchet driving wheel for said shaft; and a pawl on said actuating lever arranged to engage said shaft driving ratchet, said pawl being adapted to first disengage said locking dog and afterward advance said wheel.
4. The combination with a shaft, of a plurality of elastic aprons or belts; carrying and driving rollers for said aprons mounted on said shaft, each belt being provided with a pair of rollers, at least one of which is adapted to be moved to and from the other; latches for retaining the rollers in their closed position; a trip adapted to successively disengage said latches; pinions for the driving rollers; a driving gear therefor revolubly mounted on said shaft; a ratchet wheel connected to said driving gear; an actuating lever; a pawl thereon arranged to engage said driving gear ratchet; a ratchet driving wheel for said shaft; a locking dog; a pawl on said actuating lever arranged to engage said driving ratchet, said pawl being adapted to first disengage said locking dog and
5. The combination with a shaft, of a plurality of elastic aprons or belts; carrying and driving rollers for said aprons mounted on said shaft, each belt being provided with a pair of rollers, at least one of which is adapted to be moved to and from the other; latches for retaining the rollers in their closed position; a trip adapted to successively disengage said latches; pinions for the driving rollers; a driving gear therefor revolubly mounted on said shaft; a ratchet wheel connected to said driving gear; an actuating lever; a pawl thereon arranged to engage said driving gear ratchet; an internally-toothed ratchet driving wheel for said shaft having a flange-like periphery with holes therein spaced to correspond to its teeth; a locking dog arranged to engage said openings in the periphery of said driving wheel; a pawl on said actuating lever arranged to engage said shaft driving ratchet, said pawl being adapted to first disengage said locking dog and afterward advance said wheel; and means for securing said locking dog in its disengaging position.
6. The combination with a shaft, of a plurality of elastic aprons or belts; carrying and driving rollers for said aprons mounted on said shaft, each belt being provided with a pair of rollers, at least one of which is adapted to be moved to and from the other; latches for retaining the rollers in their closed position; a trip adapted to successively disengage said latches; pinions for the driving rollers; a driving gear therefor revolubly mounted on said shaft; a ratchet wheel connected to said driving gear; an actuating lever; a pawl thereon arranged to engage said driving gear ratchet; an internally-toothed ratchet driving wheel for said shaft having a flange-like periphery with holes therein spaced to correspond to its teeth; a locking dog arranged to engage said openings in the periphery of said driving wheel; and a pawl on said actuating lever arranged to engage said shaft driving ratchet, said pawl being adapted to first disengage said locking dog and afterward advance said wheel.
7. The combination with a shaft, of a plurality of elastic aprons or belts; carrying and driving rollers for said aprons mounted on said shaft, each belt being provided with a pair of rollers, at least one of which is adapted to be moved to and from the other; latches for retaining the rollers in their closed position; a trip adapted to successively disengage said latches; pinions for the driving rollers; a driving gear therefor revolubly mounted on said shaft; a ratchet wheel connected to said driving gear; an actuating lever; a pawl thereon arranged to engage said driving gear ratchet; a ratchet driving wheel for said shaft; a locking dog; a pawl on said actuating lever arranged to engage said driving ratchet, said pawl being adapted to first disengage said locking dog and

afterward advance said wheel; and means for securing said locking dog in its disengaging position.

7. The combination with a shaft, of a plurality of elastic aprons or belts; carrying and driving rollers for said aprons mounted on said shaft, each belt being provided with a pair of rollers, at least one of which is adapted to be moved to and from the other; latches for retaining the rollers in their closed position; a trip adapted to successively disengage said latches; pinions for the driving rollers; a driving gear therefor revolvably mounted on said shaft; a ratchet wheel connected to said driving gear; an actuating lever; a pawl arranged to engage said driving gear ratchet; a ratchet driving wheel for said shaft; a locking dog; and a pawl on said actuating lever arranged to engage said shaft driving ratchet, said pawl being adapted to first disengage said locking dog and afterward advance said wheel.

8. The combination with a shaft, of a plurality of elastic aprons or belts; carrying and driving rollers for said aprons mounted on said shaft, each belt being provided with a pair of rollers, at least one of which is adapted to be moved to and from the other; latches for retaining the adjustable rollers in their closed position; a trip adapted to successively disengage said latches; pinions for the driving rollers; a driving gear therefor revolvably mounted on said shaft; a ratchet wheel connected to said driving gear; an actuating lever; a pawl arranged to engage said driving gear ratchet; a ratchet driving wheel for said shaft; and a pawl on said actuating lever arranged to engage said shaft driving ratchet.

40 9. The combination with a shaft having spiders or heads thereon provided with radially-projecting arms arranged in coacting pairs, one arm of each pair being pivoted; a plurality of aprons or belts; driving rollers therefor arranged on said heads; carrying rollers arranged at the outer ends of said arms; friction rollers opposed to said driving rollers; compensating or tension rollers for said belts; centrally pivoted supports for said tension rollers; latches for retaining said pivoted arms in their closed positions; a trip adapted to successively disengage said latches; and driving means for said shaft and said driving rollers.

55 10. The combination with a shaft having spiders or heads thereon provided with radially-projecting arms arranged in coacting pairs, one arm of each pair being pivoted; a plurality of aprons or belts; driving rollers therefor arranged on said heads; carrying rollers arranged at the outer ends of said arms; compensating or tension rollers for said belts; centrally pivoted supports for said tension rollers; latches for retaining said pivoted arms in their closed positions;

a trip adapted to successively disengage said latches; and driving means for said shaft and said driving rollers.

11. The combination with a shaft having spiders or heads thereon provided with radially-projecting arms arranged in coacting pairs, one arm of each pair being pivoted; a plurality of aprons or belts; driving rollers therefor arranged on said heads; carrying rollers arranged at the outer ends of said arms; friction rollers opposed to said driving rollers; latches for retaining said pivoted arms in their closed positions; a trip adapted to successively disengage said latches; and driving means for said shaft and said driving rollers.

70 12. The combination with a shaft having spiders or heads thereon provided with radially-projecting arms arranged in coacting pairs, one arm of each pair being pivoted; a plurality of aprons or belts; driving rollers therefor arranged on said heads; carrying rollers arranged at the outer ends of said arms; latches for retaining said pivoted arms in their closed positions; a trip adapted to successively disengage said latches; and driving means for said shaft and said driving rollers.

75 13. The combination with a shaft having spiders or heads thereon provided with radially-projecting arms arranged in coacting pairs, one arm of each pair being pivoted; a plurality of aprons or belts; driving rollers therefor arranged on said heads; carrying rollers arranged at the outer ends of said arms; compensating or tension rollers for said belts; latches adapted to retain the pivoted arms in their closed positions; springs for said latches arranged to return said pivoted arms to their outer positions when the said latches are disengaged; a trip adapted to successively disengage said latches as the shaft is revolved; and driving means for said shaft and said driving rollers.

80 14. The combination with a shaft having spiders or heads thereon provided with radially-projecting arms arranged in coacting pairs, one arm of each pair being pivoted; a plurality of aprons or belts; driving rollers therefor arranged on said heads; carrying rollers arranged at the outer ends of said arms; latches adapted to retain the pivoted arms in their closed positions; springs for said latches arranged to return said pivoted arms to their outer positions when the said latches are disengaged; a trip adapted to successively disengage said latches as the shaft is revolved; and driving means for said shaft and said driving rollers.

85 15. The combination with a shaft having spiders or heads thereon provided with radially-projecting arms arranged in coacting pairs, one arm of each pair being pivoted; a plurality of aprons or belts; driving rollers therefor arranged on said heads; carrying

rollers arranged at the outer ends of said arms; compensating or tension rollers for said belts; latches adapted to retain the pivoted arms in their closed positions; a trip adapted to successively disengage said latches as the shaft is revolved; and driving means for said shaft and said driving rollers.

16. The combination with a shaft having spiders or heads thereon provided with radially-projecting arms arranged in coacting

16 pairs, one arm of each pair being pivoted; a plurality of aprons or belts; driving rollers therefor arranged on said heads; carrying rollers arranged at the outer ends of said 15 arms; latches adapted to retain the pivoted arms in their closed positions; a trip adapted to successively disengage said latches as the shaft is revolved; and driving means for said shaft and said driving rollers.

20 17. The combination of a plurality of elastic aprons or belts; supporting rollers for said aprons, each apron being provided with a pair of rollers, at least one of which is adapted to be moved to and from the 25 other; a support for said apron supporting rollers; compensating or tension rollers for said aprons; centrally-pivoted supports for said tension rollers; latches for retaining the rollers in their closed positions; a trip adapted to successively disengage said latches; and driving means for said aprons and said apron roller support, said apron roller support being driven with a step-by-step movement.

35 18. The combination of a plurality of aprons or belts; supporting rollers for said aprons, each apron being provided with a pair of rollers, at least one of which is adapted to be moved to and from the other; 40 a support for said apron supporting rollers; compensating or tension rollers for said aprons; centrally-pivoted supports for said tension rollers; latches for retaining the rollers in their closed positions; a trip adapted to successively disengage said latches; and driving means for said aprons and said apron roller support, said apron roller support being driven with a step-by-step movement.

45 19. The combination of a plurality of elastic aprons or belts; supporting rollers for said aprons, each apron being provided with a pair of rollers, at least one of which is adapted to be moved to and from the 55 other; a driven support for said apron supporting rollers; latches for retaining the rollers in their closed positions; a trip adapted to successively disengage said latches; and driving connections for said aprons and said apron roller support, said apron roller support being driven with a step-by-step movement.

60 20. The combination of a plurality of aprons or belts; supporting rollers for said 65 aprons, each apron being provided with a

pair of rollers, at least one of which is adapted to be moved to and from the other; a driven support for said apron supporting rollers; latches for retaining the rollers in their closed positions; a trip adapted to successively disengage said latches; and driving connections for said aprons and said apron roller support, said apron roller support being driven with a step-by-step movement.

70 21. The combination of a plurality of aprons or belts; supporting rollers for said aprons, each apron being provided with a pair of rollers, at least one of which is adapted to be moved to and from the other; a driven support for said apron supporting rollers; compensating or tension rollers for said aprons; latches for retaining the rollers in their closed positions; a trip adapted to successively disengage said latches; and driving connections for said aprons and said roller support.

75 22. The combination of a plurality of aprons or belts; supporting rollers for said aprons, each apron being provided with a pair of rollers, at least one of which is adapted to be moved to and from the other; a driven support for said apron supporting rollers; compensating or tension rollers for said aprons; latches for retaining the rollers in their closed positions; and driving connections for said aprons and said roller support.

80 23. The combination of a plurality of aprons or belts; supporting rollers for said aprons, each apron being provided with a pair of rollers, at least one of which is adapted to be moved to and from the other; a driven support for said apron supporting rollers; latches for retaining the rollers in their closed positions; a trip adapted to successively disengage said latches; and driving connections for said aprons and said roller support.

85 24. The combination of a plurality of aprons or belts; supporting rollers for said aprons, each apron being provided with a pair of rollers, at least one of which is adapted to be moved to and from the other; a driven support for said apron supporting rollers; means for retaining the rollers in their closed positions; and means for successively releasing said retaining means; and driving connections for said apron and said roller support.

90 25. The combination of an elastic apron or belt; a plurality of supporting rollers for said apron, at least one of a pair of the rollers being adapted to be moved to and from the other; compensating or tension rollers for said apron arranged in opposed pairs; centrally-pivoted supports for said tension rollers; means for retaining the movable roller in its closed position; and driving means for said apron.

120

26. The combination of an elastic apron belt; a plurality of supporting rollers for said apron, at least one of a pair of the rollers being adapted to be moved to and from the other to engage a cigar; a compensating or tension roller for said apron; a centrally pivoted support for said tension roller; means for retaining the movable roller in its closed position; and driving means for said apron. 65
27. The combination of an apron or belt; a plurality of supporting rollers for said apron, at least one of a pair of the rollers being adapted to adjust toward the other; compensating or tension rollers for said apron arranged in opposed pairs; centrally pivoted supports for said tension rollers; means for retaining the movable roller in its closed position; and driving means for said apron. 70
28. The combination with the label hopper, of a feed table; a feed carriage; a label-engaging foot carried by said carriage; clamps adapted to retain said labels in said hopper; a pair of delivery clamps pivoted at the sides of said table and adapted to swing inwardly and downwardly upon the same, said delivery clamps being provided with return ways for said label engaging foot; connections whereby said clamps are controlled by said carriage; a reservoir; a conduit on which said reservoir is pivotally mounted, said conduit having an applicator thereon adapted to be brought into contact with the label grasped by said delivery clamps; and means whereby said conduit is rocked on its pivot to bring said applicator into contact with the label on the return movement of said carriage. 75
29. The combination with the label hopper, of a feed table; a feed carriage; a label-engaging foot carried by said carriage; a pair of delivery clamps pivoted at the sides of said table and adapted to swing inwardly and downwardly upon the same, said delivery clamps being provided with return ways for said label engaging foot; connections whereby said clamps are controlled by said carriage; a reservoir; a conduit on which said reservoir is pivotally mounted, said conduit having an applicator thereon adapted to be brought into contact with the label grasped by said delivery clamps; and means whereby said conduit is rocked on its pivot to bring said applicator into contact with the label on the return movement of said carriage. 80
30. The combination with the label hopper, of a feed table; a feed carriage; a label-engaging foot carried by said carriage; a pair of delivery clamps pivoted at the sides of said table and adapted to swing inwardly and downwardly upon the same, said delivery clamps being provided with return ways for said label engaging foot; connections whereby said clamps are controlled by said carriage; a reservoir; a conduit on which said reservoir is pivotally mounted, said conduit having an applicator thereon adapted to be brought into contact with the label grasped by said delivery clamps; and means whereby said conduit is rocked on its pivot to bring said applicator into contact with the label on the return movement of said carriage. 85
31. The combination with the label hopper, of a feed carriage; a reservoir; a conduit on which said reservoir is pivotally mounted, said conduit having an applicator thereon adapted to be brought into contact with the label; and means whereby said conduit is rocked on its pivot by said carriage to bring said applicator into contact with the label. 90
32. The combination with the label hopper, of a feed table; a feed carriage; clamps adapted to retain said labels in said hopper; connections whereby said clamps are controlled by said carriage; an applicator; and means whereby said applicator is actuated to bring it into contact with the label on the return movement of said carriage. 95
33. The combination with the label hopper, of a feed table; a feed carriage; label delivery clamps; an applicator; and connections whereby said clamps and applicator are controlled by said carriage. 100
34. The combination with a shaft; a plurality of aprons, driving and supporting rollers therefor carried by said shaft; pinions for the driving rollers; a driving gear for said pinion revolvably mounted on said shaft; a ratchet wheel connected to said driving gear; an actuating lever; a pawl thereon arranged to engage said ratchet wheel; an internally toothed ratchet driving gear for said shaft having a flange-like periphery with holes therein spaced to correspond to its teeth; a locking dog arranged to engage said holes in the periphery of said shaft driving wheel; a pawl on said actuating lever arranged to engage said shaft driving ratchet, said pawl being adapted to first disengage said locking dog and afterward advance said wheel; a label feeding means; and an actuating connection therefor to said ratchet actuating lever. 105
35. The combination with a shaft: a plurality of aprons, driving and supporting rollers therefor carried by said shaft; pinions for the driving rollers; a driving gear for said pinions revolvably mounted on said shaft; a ratchet wheel connected to said driving gear; an actuating lever; a pawl thereon arranged to engage said ratchet wheel; an internally toothed ratchet driving gear for said shaft having a flange-like periphery with holes therein spaced to correspond to its teeth; a locking dog arranged to engage said holes in the periphery of said shaft driving wheel; and a pawl on said actuating lever arranged to engage said shaft driving ratchet, said pawl being adapted to first disengage said locking dog and afterward advance said wheel. 110
36. The combination with a shaft; a plurality of aprons, driving and supporting 115
37. The combination with a shaft; a plurality of aprons, driving and supporting rollers therefor carried by said shaft; pinions for the driving rollers; a driving gear for said pinions revolvably mounted on said shaft; a ratchet wheel connected to said driving gear; an actuating lever; a pawl thereon arranged to engage said ratchet wheel; an internally toothed ratchet driving gear for said shaft having a flange-like periphery with holes therein spaced to correspond to its teeth; a locking dog arranged to engage said holes in the periphery of said shaft driving wheel; and a pawl on said actuating lever arranged to engage said shaft driving ratchet, said pawl being adapted to first disengage said locking dog and afterward advance said wheel. 120
38. The combination with a shaft; a plurality of aprons, driving and supporting 125

rollers therefor carried by said shaft; pinions for the driving rollers; a driving gear for said pinions revolubly mounted on said shaft; a ratchet wheel connected to said driving gear; an actuating lever; a pawl thereon arranged to engage said ratchet wheel; a ratchet driving gear for said shaft; a pawl on said actuating lever arranged to engage said shaft driving ratchet; a label feeding means; and an actuating connection therefor to said ratchet actuating lever.

37. The combination with a shaft; a plurality of aprons, driving and supporting rollers therefor carried by said shaft; pinions for the driving rollers; a driving gear for said pinions revolubly mounted on said shaft; a ratchet wheel connected to said driving gear; an actuating lever; a pawl thereon arranged to engage said ratchet wheel, a ratchet driving gear for said shaft; and a pawl on said actuating lever arranged to engage said shaft driving ratchet, said pawl being adapted to first disengage said locking dog and afterward advance said wheel.

38. The combination with a shaft; a plurality of aprons, driving and supporting

rollers therefor carried by said shaft; pinions for the driving rollers; a driving gear for said pinions revolubly mounted on said shaft; and means for driving said shaft and said gear with a step by step movement.

39. The combination with a shaft; a plurality of aprons, driving and supporting rollers therefor carried by said shaft; pinions for the driving rollers; a driving gear for said pinions revolubly mounted on said shaft; and means for driving said shaft and said gear.

40. The combination with a shaft; a plurality of aprons, driving and supporting rollers therefor carried by said shaft; pinions for the driving rollers; a driving gear for said pinions revolubly mounted on said shaft; a label feeding means; and an actuating connection therefor to said shaft and driving gear.

In witness whereof, I have hereunto set my hand and seal in the presence of two witnesses.

FREDERICK C. HAYES. [L. S.]

Witnesses:

CLORA E. BRADEN,
F. GERTRUDE TALLMAN.
